UNITED STATES PATENT OFFICE.

SAMUEL EDWARD JENKINS, OF RICHMOND, VIRGINIA.

COW-MILKING MACHINE.

1,066,430.

Specification of Letters Patent.

Patented July 1, 1913.

Application filed December 31, 1912. Serial No. 739,556.

To all whom it may concern:

Be it known that I, SAMUEL E. JENKINS, a citizen of the United States, residing at Richmond, in the county of Henrico and State of Virginia, have invented certain new and useful Improvements in Cow-Milking Machines, of which the following is a specification.

This invention relates to certain improvements in and relating to milking machinery; and the objects and nature of the invention will be readily understood by those skilled in the art in the light of the following explanation of the accompanying drawings illustrating what I now believe to be the preferred embodiment from among other formations, arrangements and combinations within the spirit and scope of my invention.

The invention consists in certain novel features in construction and in combinations of elements as more fully and particularly set forth hereinafter.

Referring to the accompanying drawings: Figure 1, is a perspective view of a machine constructed in accordance with my invention, certain parts being shown in normal lowered or inoperative position. Fig. 2, is a side elevation, dotted lines showing certain parts elevated to operative position. Fig. 3, is a top plan view. Fig. 4, is a vertical longitudinal section, on an enlarged scale, through a portion of the machine. Fig. 5, is a cross section on the line 5—5, Fig. 3. Fig. 6, is a detail vertical section. Fig. 7, is a detail perspective. Fig. 8, is a detail horizontal section in the plane of the line 8—8, Fig. 5.

In the particular embodiment illustrated as an example for purposes of explanation, 40 the machine is portable and comprises a supporting stand, frame or truck. In this example, the supporting frame or truck consists of a pair of rear corner posts or uprights upheld by and at their lower ends 45 provided with supporting wheels or casters 1, said uprights being rigidly connected together by elevated transverse rigid cross bar 2; front corner posts or uprights 3, rigidly connected at their upper ends by elevated 50 cross bar or member 4, and at their lower ends provided with supporting wheels or casters 5; a rigid vertical depending socket, bearing or tubular member 6, arranged centrally between the elongated front legs or 55 posts 3, and at its upper end rigid with cross member 4; and a rigid horizontal

longitudinal reach bar or member 7, at its rear end rigid with cross bar 2, and at its front end rigid with the depending tubular member 6, and carrying the operator's seat 8, mounted on seat post 9, rising from and carried by reach bar 7. However, I do not wish to limit myself to any particular supporting stand or truck construction, nor in fact are other features of my invention limited to any particular construction or arrangement of supporting means, whether involving a wheeled truck or any other supporting frame. My invention involves peculiar mechanism for manipulating the cow's teats to cause flow of milk from the udder through the teats, and such mechanism is designed to imitate, to a certain extent, the milking operation of the human hand and to a certain extent the nursing operation of a calf although omitting the suction action.

I usually provide four similar simultaneously operating pairs of teat applicators, massaging or compressing devices, one for each teat. Each device consists of a pair of vertically elongated opposing jaws, applicators or presser members having longitudinally concaved soft or elastic opposing faces to longitudinally receive and confine the teat. The teat engaging faces of the jaws are composed of longitudinal blocks 10, of any suitable soft or elastic material such as rubber or the like, and these blocks are centrally and longitudinally depressed or concaved throughout the lengths of their teat engaging faces to provide the longitudinal teat receiving dépression 11. Each jaw is formed of a longitudinal body or holder 12, usually formed of metal and providing a longitudinal downwardly tapered socket to removably receive a downwardly tapered soft block or teat engaging body 10, and flanges 13, for confining the block 10, in the holder, so as to permit removal thereof when necessary for cleansing, repair or renewal. The jaws of each pair are preferably similar in construction in so far as the holders and soft material blocks just described are concerned, but said jaws are differently-mounted and are so arranged that in action one jaw *a*, is fixed or stationary while the other jaw *b*, is bodily movable toward and from the fixed jaw to bring the movable jaw into and from operative position with respect to the teat and furthermore is rockable on a transverse axis to

massage or manipulate the teat in the required manner to cause the flow of milk.

In the particular example illustrated, I show a group of four similar pairs of teat pressing applicators or jaws arranged in two longitudinal rows and in two transverse rows. The four pairs of jaws are carried and supported by a suitable frame work comprising the two main supporting side rods 15, and a pair of parallel spaced cross rods 16, extending between and connecting the side rods and at their ends coupled thereto by sleeves 17, loosely receiving said side rods and slidably longitudinally thereon. Each cross rod 16 carries a pair of opposite fixed jaws *a*. Each jaw *a*, has a transverse eye 18, through which its supporting rod 16, passes, said eye being longitudinally slidable on its supporting rod and adapted to be clamped thereto in the desired adjustment by set screw 19. The movable jaws *b*, are carried by longitudinal slides or reciprocating frames 20, arranged above and spaced from the cross rods 16, and carried by and slidable through guides 21, projecting laterally from the upper ends of the side edges of the fixed jaws *a*. Each movable jaw is hung from its supporting slide, 20, to swing on a transverse axis or pivot arranged in rear of the upper portion of the jaw and a short distance below the upper extremity of the jaw. In the particular example illustrated, each movable jaw is formed with a rearwardly extending rib providing laterally projecting aligned pintles or trunnions 22, fitting and turnable in sockets in the brackets 23 mounted on the opposite sides of the slide 20, carrying such jaw. These brackets 23, are adjustable longitudinally of the slide 20, to adjust the movable jaw and are normally fixed thereto by suitable set screws. The pintles 22, constitute the transverse axis or pivot on which the movable jaw swings as hereinbefore described, although of course other means for rockably mounting jaws *b*, can be provided.

I show two parallel slides 20, one for each longitudinal row of pairs of jaws, and each slide is carried by and freely slidable through the two fixed jaws of its row and carries the two movable jaws of its row. These two slides are connected together at their rear ends by a cross bar 24, to cause the slides to reciprocate in unison. The slides are coupled to the cross bar 24, by sleeves 25, slidably longitudinally of said cross bar so that the slides can be adjusted toward and from each other to vary the distance between the two longitudinal rows of pairs of jaws when the set screws 19, are loosened so that the fixed jaws can be moved longitudinally of their supporting rods 16. The pairs of jaws can be adjusted toward and from each other longitudinally of the slides by sliding the cross rods 16, on the

side rods 15, after the various set screws clamping the sleeves and guides to the rods 15, and the slides have been loosened. By these adjustments the distances between the pairs of teat jaws can be varied to properly locate said pairs wherever necessary to accommodate the teats of the particular cow to be milked. The supporting frame for the fixed jaws comprising rods 15, 16, is normally supported in a fixed position, while the slides are longitudinally reciprocated to completely open the pairs of jaws (Fig. 3) to receive the teats, or to close said jaws on the teats and to operative position (Fig. 4). These slides can be moved longitudinally and held in the desired position by various means although in the example illustrated, I provided a reciprocatory connection or pull rod 26, for this purpose at its front end detachably coupled to the cross rod 24, through the medium of a socket 27, and its set screw.

Various means can be provided to swing or rock the movable jaws while said jaws are held by the slides 20, in operative position holding the teats against the fixed jaws. For instance, I show a reciprocatory rod 28, arranged longitudinally of the rows of jaws and adjustably carrying cross rods 29, loosely extending through eyes 29^a, projecting from the front sides of the lower ends of the movable jaws, so that longitudinal reciprocation of the rod 28, will simultaneously swing or rock all of the movable jaws on the transverse axes 22. In the particular example illustrated, I show an open-top horizontal tank 30 for supporting the teat jaw carrying frame and the means for collecting the milk. The teat frame carrying the teat jaws is horizontally and removably arranged within this tank, so that the teat jaws are vertically arranged in the tank and spaced from the side walls and bottom thereof.

Various means can be provided to removably support said frame within the tank although in the particular example illustrated, I show said tank internally provided with elevated corner supports or ledges 31, to removably uphold said frame within the tank and so that the frame can be moved to and from the tank through the open top thereof. I show said frame upheld in the tank by the ends of the frame bars 15, resting on said ledges 31. I show the tank provided with a removable horizontal pan or flanged false bottom 32, arranged below the teat jaws to receive the milk from the teats. This pan is provided with a screened bottom discharge opening 33, immediately over the open receiving end of a horizontally disposed discharge spout 34, arranged below the tank 30. This spout as shown is formed at its open receiving end with an upturned annularly and outwardly flanged neck 35,

passing up through an opening in the bottom of the tank with its flange resting on the top face of an annular depressed seat in the bottom of said tank so that the spout 5 can swing horizontally on said neck as its vertical axis. I show the spout extending rearwardly to discharge milk into a bucket or other receptacle. A transversely arranged fixed guide or support 36, can be 10 provided on which the free end of the spout rests and on which it is slideable to the right or left to discharge the milk into the bucket whether located at the right or left hand side of the machine.

15 Various means can be provided for carrying the tank 30, in a projected or advanced position beneath a cow and for elevating the tank to the udder to bring the teat jaws into operative position with respect thereto. I 20 show a supporting arm or horizontally arranged and elongated frame 38, at one end fixed to the tank 30, so that the tank in effect constitutes a forward or longitudinal continuation of said supporting arm. At its 25 opposite end said arm 38, is provided with a vertical spindle 39, rigid therewith and depending therefrom in the tubular member 6, of the wheeled truck. The spindle is vertically movable in said tubular member to 30 support and guide the supporting arm 38, in its vertical movements, and said spindle also forms a pivot or axis permitting said arm to swing laterally, in which event said spindle turns or rotates in said tubular 35 member.

39^a, is a cushioning spring arranged in the lower end of the socket 6, to act on the spindle 39, when it drops under the load of the arm 38 and parts carried thereby, to 40 cushion the shock.

Various means can be provided for elevating the arm 38, and the tank 30, carried at the free end thereof, and for controlling the vertical position of the tank. For instance, I show a vertically swingable yoke or lever 40, hinged or fulcrumed at 41, on transverse aligned pivots to the upper ends of the truck posts or uprights 3, and from thence extending forwardly and horizontally and at its front free end provided with a transverse portion 42, extending beneath and loosely engaging a longitudinal member or portion of the arm 38. This transverse end portion 42, of the lever is formed with 45 a top socket or depression 43 immediately to the right of a vertical stop 44. The lifting lever is provided with an extension projecting rearwardly beyond the lever fulcrum and forming a handle 45. I preferably provide 50 a vertically movable and horizontally rockable treadle or double foot piece 46, arranged below the handle 45, and connected thereto by flexible pull connection 47. The treadle is formed with a central vertical 55 sleeve 48, slideable vertically and rotatable 60 sleeve 48, slideable vertically and rotatable 65

on a rigid vertical post 49, fixed to and rising from the reach bar of the stand or truck so that the treadles 46, are readily accessible to the operator sitting on the seat 8.

Suitable means readily accessible to the operator on the seat 8, are provided for closing the pairs of teat jaws together and holding the same in such operative position, and also for oscillating or rocking the movable jaws, while thus held in operative position, 70 to massage or manipulate the teats to force the milk therefrom and into the milk collecting pan 32. For instance, I show the slide rod 26, extended through an opening in the rear end of the tank 30, and loosely 75 and longitudinally through the arm 38, and at its rear end, at a point accessible from the seat 8, provided with a pull handle 50 rigid therewith and by which the rod 26, can be pulled rearwardly to draw the slides 80 rearwardly and thereby close the pairs of teat jaws together and hold them in such operative position. In the example illustrated, the arm or elongated frame 38, is composed of several parallel longitudinal 85 tubular members and rigid vertical connecting members, and I show the pull rod 26, extending longitudinally and loosely through the upper longitudinal tubular member of said arm. This upper tubular member is 90 directly coupled to the upper end of the arm-carrying spindle 39, and is provided with a horizontal rearward extension 51, having a longitudinally bifurcated rear end between the legs of which the vertically arranged handle 50, is confined to reciprocate. The legs of said bifurcated end are formed with longitudinal slots 52, and the handle 50, with lateral stops 53, confined to reciprocation in said slots to limit the reciprocation 95 of the handle and consequently of the pull 100 rod 26.

A coiled expansion spring 54, is arranged (see Fig. 6) in the rear extension 51, between an end shoulder thereof and an abutment on the pull rod 26, to yieldingly hold said pull rod and the handle 50, at their limits of forward movement and hence to yieldingly hold the teat jaws in open or inoperative position. When the handle 50, is 110 pulled rearwardly and the pairs of teat jaws are thereby closed to operative position, the spring 54, is compressed, so that the instant the handle 50, is released from the pull of the operator's hand, the spring 54, will automatically return the handle 50, and rockable 115 teat jaws to normal positions, thereby opening the pairs of teat jaws to release the teats. 120

Suitable means, accessible from the seat 8, are provided to reciprocate the rod 28, 125 and thereby oscillate or rock the rockable teat jaws b. In the example illustrated, I show a hand lever 55, for this purpose, operatively connected with rod 28, through the medium of reciprocatory slide rod 56, 130

and link 57. The slide 56, is carried by and longitudinally movable in the lower longitudinal tubular member of the arm 38, and extends therefrom into the tank 30, and at 5 its front end is detachably coupled to the rear end of rod 28, by removable coupling pin 58. The rear end of slide 56, in rear of said tubular arm member, is pivotally joined to the lower end of hand lever 55, 10 by the pull link 57, slideable through guides 59, on the lower end portion of handle 50, and at its rear end pivotally joined to the lower end of said hand lever. The hand lever 55 is arranged vertically beside the 15 handle 50, and intermediate its length is mounted on said handle through the medium of transverse or horizontal fulcrum 60, so that oscillation of said lever will reciprocate the rod 28, and cause the teat manipulating 20 rocking movement or oscillation of the teat jaws *b*. A coiled spring 61, constantly acts on the teat jaws *b* to yieldingly hold the lower ends thereof swung to their limits of movement away from the lower ends of 25 fixed jaws *a*, with the upper ends of the pairs of jaws closed together. This spring 61, also yieldingly holds the hand lever 55, with its upper or handle end swung to its 30 limit away from the handle 50.

In operation, the machine is wheeled up to the right hand side of the cow so that the tank 30, is arranged directly under the udder. The tank 30, is elevated to bring the teat jaws into proper position lengthwise of the teats (located in the open pairs of jaws) 35 and bearing upwardly against or lifting the udder. The tank 30, is elevated by the operator on seat 8. The operator places his feet on treadle 46, and bears down thereon 40 and also by hand bears down on handle 45, and the lever 40, is thereby swung upwardly so that its front end 42, bears upwardly against the arm 38 and slides rearwardly thereon and thereby elevates said arm and 45 its spindle 39, to carry the tank 30 to the desired elevated position. The operator holds the tank thus elevated by keeping his feet on treadle 46. The spindle 39, slides upwardly in its vertical socket and thereby 50 guides the arm 38, and tank 30, to direct vertical movement in a straight line. When the operator is assured that the teats are all properly located in the open pairs of jaws, he pulls back on the handle 50, and thereby 55 closes said jaws together at their upper ends to compress the teats at their bases or upper ends. While holding back on the handle 50, against the tension of spring 54, the operator then presses the upper end of the hand lever 55, forwardly, and thereby rocks the jaws *b*, on their transverse axes so that their lower ends swing rearwardly toward the lower ends of the fixed jaws. This action 60 transversely compresses the teats progressively from the udder toward their lower 65

ends to force the milk from the teats. When the lower ends of the jaws are approximately closed together, said jaws have slightly opened at their upper ends. The operator while holding back on the handle 50, uses the same hand in rocking the lever 55, held by spring 61, back and forth, as described, to produce the peculiar teat manipulating, pressing or massaging action of the jaws to force the milk from the teats. The tank 70 30, when lifted by the arm 38, causes the upper rounded soft ends of the teat jaws to press upwardly against and lift the udder to imitate the action of a calf in "hunching" the udder when nursing, whereby certain 75 advantages are attained. The operator always has the pairs of jaws under perfect control and can vary the pressure thereon and permit the same to completely open whenever desired. 80

If the cow should start forward while the tank 30, is in operative position, no damage need be done, for when the cow's leg strikes the tank or the tank supporting arm, the entire structure can swing forward with the 90 spindle 39, turning in socket 6, as the arm will be forced out of the holding depression 43, in the front end of lifting lever 40, and will slide forwardly on the free end of said lifting lever, being supported by the spindle 95 39. The treadle 46 can also swing on its post 49, so as not to obstruct the arm in this swinging. The arm can be swung back against stop 44, and to normal position. It should also be noted that the frame work 100 carrying the jaws can be lifted bodily from the tank with the jaws for cleansing or other purposes and that the milk collecting pan 32, can then also be lifted from the tank so that the interior of the tank and spout 34, 105 can be inspected and cleaned. In order to free the jaw carrying frame for removal from the tank, it is only necessary to detach the removable operative connections between slide rod 26, and cross bar 24, and 110 between reciprocating rod 28, and its operating connection 56.

It is obvious that various changes, modifications and variations might be resorted to, that features might be omitted and structures added, without departing from the spirit and scope of my invention and hence I do not wish to limit myself to the exact disclosure hereof. 115

What I claim is:—

1. In milking apparatus, a horizontally-disposed open-top tank provided with a removable milk-collecting pan arranged within the tank, said tank provided with a bottom discharge, said pan having an outlet 125 to said discharge, supporting means for said tank, and teat receiving and manipulating means in said tank and provided with actuating devices.

2. In milking apparatus, supporting 130

means, mechanism for raising and lowering the same, a milk-collecting receptacle in said means having a milk discharge comprising a laterally swingable discharge spout, and teat-receiving and manipulating devices carried by said supporting means and arranged over said receptacle to force milk from the teats into said receptacle, said teat receiving devices provided with actuating means.

3. Milking apparatus comprising a portable stand, an elevated arm projecting horizontally therefrom, manually actuated means for elevating said arm and controlling the vertical position thereof, milk-collecting and discharging means carried by the free end of said arm, and teat-receiving and manipulating devices carried by the free end of said arm for forcing milk from the teats and into said milk collecting means.

4. A milking machine comprising a portable stand, a laterally-swingable and vertically-movable arm projecting horizontally from said stand and at its free end provided with and carrying teat-receiving and manipulating devices for forcing milk from the teats, means for actuating said teat manipulating devices, and mechanism for controlling the vertical position of said arm and teat devices with respect to said stand.

5. A milking machine comprising a portable stand having an operator's seat and provided with a vertically movable treadle and with a vertically swingable hand lever operatively connected by a pull connection with said treadle, a vertically movable arm carried by said stand, said arm being elevated by said lever and held thereby in the desired vertical position, teat receiving and manipulating devices carried by said arm, and operating connections for said devices.

6. A milking machine comprising supporting means, a series of normally fixed teat receiving jaws, a series of corresponding teat receiving jaws, means whereby said corresponding teat receiving jaws are mounted to rock on transverse axes, a slide carrying said corresponding jaws bodily toward and from said fixed jaws, a handle for moving said corresponding jaws through the medium of said slide to said fixed jaws, a spring mechanism for yieldingly holding said corresponding jaws in the opposite direction, and means for rocking said corresponding jaws comprising a spring device yieldingly holding said jaws in one direction and a hand lever carried by said handle for rocking said jaws in the opposite direction.

7. In milking apparatus, a pair of coöperating teat receiving and manipulating jaws, devices for opening and closing said jaws comprising means yieldingly maintaining said jaws open and manually controlled means for holding said jaws closed against the tension of said means, and mech-

anism for gradually closing said jaws toward each other from the upper ends thereof toward the lower ends thereof.

8. In milking apparatus, several normally-fixed vertically disposed teat receiving jaws, corresponding means for holding the teats to said jaws and for laterally compressing the teats there against progressively from their upper portions to their lower portions to force milk therefrom, supporting mechanism, actuating devices for said means, said jaws and corresponding means being normally and yieldingly held in open inoperative position, and manually actuated devices for yieldingly holding the same in closed operative position.

9. In milking apparatus several normally-fixed vertically disposed teat receiving jaws, corresponding means for holding the teats to said jaws and for laterally compressing the teats there against progressively from their upper portions to their lower portions to force milk therefrom, supporting mechanism, actuating devices for said means, said pairs of jaws and corresponding means being relatively movable to and from closed operative and open inoperative positions, and hand actuated devices for yieldingly holding said jaws and corresponding means in closed position during said teat compressing operations of said corresponding means.

10. In milking apparatus, in combination, a series of pairs of coöperating teat manipulating jaws, spring means yieldingly maintaining the pairs of jaws separated in opened position, hand operated connections for yieldingly holding the jaws in operative teat pressing position against the tension of said spring means, and manually operated means for rocking certain of said jaws to progressively compress the teats from their upper ends toward their discharge ends while said pairs of jaws are held in operative position.

11. A milking machine comprising supporting means, a series of normally fixed teat receiving jaws, a series of corresponding teat receiving jaws, means whereby said corresponding jaws are mounted to rock on transverse axes, manually controlled means for moving said corresponding jaws bodily toward and from said fixed jaws, and means for rocking said corresponding jaws comprising a spring device yieldingly holding said jaws in one direction and a manually controlled device for rocking said jaws in the opposite direction.

12. A milking machine comprising supporting means, a series of normally fixed teat receiving jaws, a series of corresponding teat receiving jaws, means whereby said corresponding jaws are mounted to rock on transverse axes, a slide carrying said corresponding jaws bodily toward

and from said fixed jaws, a handle for moving said corresponding jaws through the medium of said slide to said fixed jaws, a spring mechanism for yieldingly holding 5 said corresponding jaws in the opposite direction, and means for rocking said corresponding jaws.

13. In milking apparatus, in combination, supporting means, a series of pairs of teat 10 manipulating members, a slide for opening and closing said pairs of members by moving the same bodily, manual operating means for said slide, a spring device yieldingly holding said slide in one direction, and 15 manually actuated means for operating said members to manipulate the teats.

14. In milking apparatus, in combination, a pair of teat manipulating members, one 20 of said members being mounted to rock on a transverse axis, said members being relatively movable to and from opened inoperative and closed operative positions, a handle connected to yieldingly hold said members in closed operative position, and 25 means for rocking said rockable member while said members are held in closed position by said handle.

15. In milking apparatus, in combination, a pair of teat manipulating members, one 30 of said members being rockable independently of the other member, said members being relatively movable to and from opened inoperative and closed operative positions, a handle connected to yieldingly hold said 35 members in closed operative position, and means for rocking said rockable member while said members are held in closed position by said handle, said means comprising a manually actuated device.

40 16. In a milking apparatus, in combination, a pair of teat manipulating members, one of said members being rockable independently of the other, said other member being movable to and from closed operative 45 position with respect to the rockable member, a manually operated device connected to yieldingly hold said other member in closed operative position, and means for rocking said rockable member comprising a spring device yieldingly holding said member in one direction and a hand lever carried by said manually operated device for swinging said member in the opposite direction.

55 17. A milking machine comprising a stand, a vertically movable arm carried and guided by said stand and projecting forwardly therefrom and at its free end provided with and carrying teat receiving and

manipulating devices, a vertically movable 60 hand lifting lever fulcrumed separately from said arm for raising said arm and determining the vertical position thereof, and operating means for said teat receiving devices. 65

18. A milking machine comprising a stand having a vertical guide, a vertically swingable lever fulcrumed to said stand, an arm extending forwardly from said stand and at its free end provided with milking 70 devices, manually controlled actuating means for said milking devices, said arm provided with a post confined to said guide and vertically movable therein as the arm is raised and lowered, said arm being raised 75 by said lever and maintained thereby in the desired vertical position.

19. A milking machine comprising a stand having a vertical guide, a laterally-swingable and vertically-movable arm having a post turnable in said guide to center said arm as it swings laterally and movable vertically in said guide with said arm, said arm at its free end provided with milking devices, and a manually-operated vertically- 80 swingable lever fulcrumed to said stand separately from said arm to raise the arm and determine the vertical position thereof, said arm resting on said lever and swingable laterally independently thereof. 85

20. A milking machine comprising a stand, a vertically movable arm extending forwardly therefrom, and at its free end provided with milking devices, and means for freely elevating and depressing said 95 arm and for maintaining the same at the desired elevation comprising a foot piece whereby said arm can be held in the desired elevated position by the foot. 90

21. In milking apparatus, in combination, 100 a support, a pair of fixed teat jaws, a rod for supporting the same, said rod being adjustably supported, said jaws being independently adjustable longitudinally of the rod, a pair of rockable jaws cooperating 105 with said first mentioned jaws, a slide carrying said rockable jaws, said rockable jaws being adjustable toward and from each other, means for reciprocating said slide, and reciprocating means for rocking said 110 rockable jaws.

In testimony whereof I affix my signature in presence of two witnesses.

SAMUEL EDWARD JENKINS.
